HYDRAULIC APPARATUS

Joseph H. Kerber, Milwaukee, Wis., assignor to
 Hi-Way Service Corporation, Milwaukee, Wis.,
 a corporation of Wisconsin

Application July 28, 1933, Serial No. 682,571

3 Claims. (Cl. 103—2)

The invention relates to hydraulic power producing apparatus.

One of the great problems with hydraulic apparatus is the liability of leakage and the necessity in most cases for the use of stuffing boxes to prevent leakage and the liability of the stuffing boxes not functioning properly due to neglect or wear. Where the hydraulic equipment is in the hands of unskilled users, as is frequently the case, this matter of leakage is a serious one from an operating and maintenance standpoint. It is one of the objects of the present invention to provide an hydraulic apparatus wherein the pump and the control valve mechanism are mounted in a casing containing the working fluid and any leakage from the high pressure side of the pump and valve is free to drain into the casing.

A further object of the invention is to provide a high pressure pump unit enclosed within a casing containing the working fluid for said unit, said unit having an operating connection extending from said casing which only needs to be sealed against the relatively small static head of fluid in said casing.

The invention further consists in the several features hereinafter set forth and more particularly defined by claims at the conclusion hereof.

In the drawings:

Fig. 1 is a vertical sectional view through an apparatus embodying the invention, parts being broken away and the section being taken along the line 1—1 of Fig. 2;

Fig. 2 is a vertical sectional view taken generally along the broken line 2—2 of Fig. 1;

Fig. 3 is a detail horizontal sectional view taken on the line 3—3 of Fig. 1;

Fig. 4 is a detail horizontal sectional view taken on the line 4—4 of Fig. 1;

Fig. 5 is a view similar to Fig. 4 showing the valve in a different position.

Referring to the drawings, the numeral 6 designates a base member, 7 a head member, and 8 a tube or wall member having fluid tight connection at its ends with said base and head members and forming a casing therewith into which oil or other suitable working fluid is introduced through a filling opening 9 normally closed by a pipe plug 10 provided with a vent opening 11.

A pump block or body 12 is provided with spaced bores 13 in which the plungers 14 reciprocate. The body 12 is securely clamped to the base 6 by bolts 15 extending up through the base 6 and into said body, the ends of the bores 13 be-

ing sealed by copper gasket rings 16 put under compression by the clamping of said body to said base. Vertically disposed passages 17 are formed in the base 6 and communicate with the bores 13. The upper end of each passage 17 has a pipe thread formed therein in which the tapered threaded end 18 of the casing 19 for the discharge valve is fitted. The casing 19 has a discharge passage extending through it with a reduced opening 20 in its upper end adapted to be closed off by a ball valve 21 during the suction stroke of the pump, said ball being limited in its movement by a pin 22 extending transversely through the side walls of said casing 19 and having a drive fit therein. The passages 17 are connected together by a passage 23 and to a common discharge pipe 24 by the passage 25 extending from one end of the passage 23.

A laterally disposed inlet passage 26 communicates with each bore 13 and has a pipe threaded outer end adapted to receive the tapered threaded end 27 of the casing 28 for the inlet valve. The casing 28 has a passage extending through it with a reduced opening 29 in its upper end adapted to be closed off by a ball valve 30 during the discharge stroke of the pump, said ball being limited in its movement by a pin 31 extending transversely through the side walls of said casing 28 and having a drive fit therein. The passages of the inlet valves communicate directly with the interior of the casing formed by the members 7, 8 and 9.

The base member 6 forms the head end of the pump and it has a conically inclined edge or seat 32 adapted to receive a similarly inclined edge 33 of the tube 8 to form a fluid tight joint therewith. The upper end of the tube has an inclined edge 34 that seats against a similar edge 35 formed on the head 7 and bolts 36 extend through the head 7 and into the body 12 and clamp the head 7 and tube 8 together and the tube against the base 6.

Each plunger 14 is operatively connected by a link 37 to one arm of an oscillatory lever 38 which is connected by a screw 39, having a tapered pin end, to the shaft end 40 of an operating crank 41, said shaft being journalled in bearing bosses 42 formed in parts of the body 12. The shaft 40 extends through an opening 43 in the side wall of the casing enclosing the pump body 50 and a tubular boss 44 is welded or otherwise suitably secured to the tube 8 adjacent this opening and has a sealing means mounted therein including a flexible sealing ring member 45 held against the shaft by a suitable spring 46, it being noted 55

that this sealing means is not a heavy duty seal but only has to seal against the static head of fluid in the casing containing the pump body. The crank 41 is shown as provided with an operating handle extension 47 and it is to be noted that the tube 8 may be positioned as to bring the operating crank at either the left or right hand side of the pump.

The control valve mechanism includes a valve 10 housing 48, a plug valve 49 associated with said housing, and means for operating said valve.

The housing 48 has a tubular end portion 50 and a shoulder 51 adjacent thereto, said portion 50 projecting through an opening 52 in the head member 7 and the flat shoulder 51 being clamped to the head adjacent said opening by a nut 53 engaging the outer threaded end of said tubular portion 50.

The plug valve 49 has a tapered valve portion 20 54 fitting the similarly tapered bore 55 of the housing 48 and a shank 56 extending through the tubular end portion 50 and provided with a polygonal end 57 upon which the socketed end of an operating handle 58 is mounted. The valve 25 is normally held in seating relation with the housing by a spring 59 interposed between the end of said valve and a plug 60 which has threaded engagement with the threaded end 61 of said housing.

30 The valve 49 is adapted to control the flow of working fluid from the discharge of the pump and back to the suction side thereof and in the present instance control the ports 62, 63, 64 and 65 in the casing 48, said valve having recesses 66 formed 35 therein so that two ports may be bridged or connected together at one setting of the valve.

The pipe 25 conducts the discharge from the pump to the port 64 while pipes 67 and 68 connect the ducts 63 and 65 with passages 69 and 40 70 in the base 6 from which the pipes 71 and 72 lead to the device to be operated. A pipe 73 connects the port 62 with the space surrounding the pump and extends down to a position adjacent the bottom of said space. When the valve 45 is in the position shown in Fig. 4 the pump is shut off. When the valve is in the full line position shown in Fig. 5, the discharge from the pump coming from pipe 25 passes through port 64 across one of the recesses 66 to the port 65 and thence 50 through pipe 68 and passage 70 to the pipe 72 while fluid may be returned through pipe 71, passage 69, pipe 67, duct 63, recess 66, duct 62 and pipe 73 to the suction side of the pump. Another position is shown by dotted line in Fig. 5, 55 wherein the pressure fluid is conducted to the pipe 71 and the fluid returned by way of pipe 72, it being understood that the pipes 71 and 72 communicate with different parts of a hydraulically operated device, for example, opposite sides of 60 an hydraulically operated piston.

The valve 49 works under high pressure and to prevent leakage along the shank 56 to the out-

side, a groove 74 is formed adjacent the head 54 of the valve and communicates with a duct 75 in the housing 48 which leads to the space within the tube 8 so that any leakage from the valve is returned back to the suction side of the pump. It is also to be noted that the pipes 25, 67, 68 and 73 are also disposed in the casing enclosing the pump and valve and that the shaft 40 may be secured in position after the casing parts have been assembled as access of a screw driver or other suitable tool to the interior of said casing to manipulate the screw pin 38 may be had through the opening 8.

From the foregoing description it will be noted that any leakage past the pump plungers 14 or 15 from the valve 49 will be delivered to the space 16 enclosing the pump and the valve so that the use of stuffing boxes to seal against high pressures is avoided.

I desire it to be understood that this invention 20 is not to be limited to any particular form or arrangement of parts except in so far as such limitations are included in the claims.

What I claim as my invention is:

1. In an hydraulic apparatus, the combination 25 of a base, a pump cylinder mounted on said base, a plunger working in said cylinder, a head member, a control valve operatively connected to said pump cylinder and mounted on said head member and controlling the discharge from said pump, 30 a casing member having a fluid tight connection with said base and head member and forming therewith an enclosing casing for said pump cylinder, plunger and valve, and means for actuating said plunger including a shaft extending through 35 a wall of said casing member.

2. In an hydraulic apparatus, the combination 40 of a plunger type pump, a housing enclosing the high pressure working parts of said pump and communicating with the suction side of said pump, a valve housing mounted on said first named housing, a conduit connecting said housing with the discharge side of the pump, a valve mounted in said valve housing and having an exteriorly extending operating shank and controlling the discharge from said pump, and means for returning any leakage along said shank into 45 said first named housing.

3. In an hydraulic apparatus, the combination 50 of a base having discharge passages, a pump cylinder mounted on said base and having a bore communicating with one of said passages, a plunger working in said bore, a head member, a control valve mounted on said head member and operatively connected to said pump discharge 55 passage and to another of said discharge passages in said base, a casing member having a fluid tight connection with said base and head member and forming therewith an enclosing casing for said pump cylinder, plunger and valve, and means for actuating said plunger.

JOSEPH H. KERBER.
